UNITED STATES PATENT OFFICE.

WILLIAM P. GOOLMAN, OF LOS ANGELES, CALIFORNIA, ASSIGNOR OF
ONE-HALF TO JOSHUA G. WICKERSHAM, OF SAME PLACE.

TIRE-TIGHTENER.

SPECIFICATION forming part of Letters Patent No. 594,992, dated December 7, 1897.

Application filed October 28, 1896. Serial No. 610,383. (No model.)

To all whom it may concern:

Be it known that I, WILLIAM P. GOOLMAN, of Los Angeles, in the county of Los Angeles and State of California, have invented a new 5 and Improved Tire-Tightener, of which the following is a full, clear, and exact description.

The invention relates to tire-tighteners such as shown and described in Letters Patent 10 No. 213,412, granted to me March 18, 1879.

The object of my improvement is to provide an instrument with which a loose tire on a vehicle may be tightened without having to remove it from the wheel. It is intended for 15 use by all who use wagons and buggies, and more especially in hot dry climates, where tires must be tightened often. I attain these objects by the instrument illustrated in the accompanying drawings, in which—

20 Figure I is a front view of the tightener as it appears when in use; Fig. II, a side view showing the working parts; Fig. III, a detached view of the wedge; Fig. IV, a detached view of the link; Fig. V, a sectional view of 25 the standard and shoe on line L L, where the shoe is jointed to the standard.

Similar letters indicate like parts throughout this description.

To the standard A is jointed a shoe B near 30 its lower end, as shown at E. This standard is an iron casting formed with three sides, leaving it hollow and open at the front, as shown in Fig. V. The top of said standard projects forward and is provided with a hole for admitting an ordinary bolt D. The bottom of said standard is grooved transversely at the back, as shown at N, to admit the link G, and is also provided with a projecting bead H at the bottom, on which the link G may rest 35 40 while being placed in position.

The wedge F is double concave, as shown in Fig. III. The thickest part of the small end of this wedge is the same diameter as the thin portion of the large end of the wedge, so 45 that it may be reversed from the position shown in Fig. II when the spoke is so small that the thin end will not draw the link tight enough.

The lifting-stirrup C is an iron casting with 50 a thin web body, with ribs extending from the top portion, (which projects forward,) down

the back of the plate or web, under the bottom, and then projecting forward, forming the hooks c c. In the top of this stirrup C, where it projects forward, is cast a recess to admit the 55 bead of the bolt D and prevent its turning. This improved form of the stirrup (with web-body and ribs) is to admit of the upper end of the standard A being drawn forward between the ribs when the bolt D is tightened, 60 also preventing the bolt from turning, as described.

The operation of tightening a tire with this instrument is as follows: The bolt D is passed through the hole in the stirrup C and up 65 through the hole in the standard A and the nut d started on. The tightener is then placed with the hooks c c under the felly of the wheel, with the concave shoe on standard, resting against the back of the spoke. That brings the 70 link G forward past the front of the spoke. The wedge F is slipped under the points of the link. Turn the nut d slightly and the link will be drawn tight on the wedge and prevent any slipping on the spoke. This is the main 75 feature of improvement over my first patent referred to. In the first one there was no jointed shoe on the standard A. It depended on the standard resting against and slipping down the spoke as the bolt was tightened until the link drew tight and held fast. In this 80 improvement there is no slipping on the spoke, therefore no danger of marring the paint. The reason for this is obvious. The shoe B being pivoted to the standard A out 85 of line with the bolt D, the moment the bolt begins to draw the upper end of the standard is drawn forward. Therefore its lower end below the pivot is thrown out, drawing directly on link G, which causes the wedge F and shoe 90 B to bind the spoke as in a vise. The more pressure the tighter the grip on the spoke. Continue tightening the bolt D, and the hooks c c under the felly lift it from the shoulder of the spoke and tight against the tire, at the 95 same time forcing the spoke down into the hub. When the felly is so lifted, a washer is slipped under it and around the small pin on the spoke. The bolt is then slackened up and the tightener removed to another spoke.

I am aware that my prior patent covers portions of this instrument, but

What I claim as new, and wish to secure by Letters Patent, is—

The combination in a tire-tightener of a shoe B, jointed to an iron standard made with three

5 sides leaving a recess (or hollow) open at one side, in which the shoe is pivoted forming a fulcrum for the standard whereby the standard is made to act as a lever, its lower end drawing directly on the link G, when the

bolt D, is tightened, clamping the spoke between the wedge F, and shoe B, with a vise-like grip, substantially as shown and described.

WILLIAM P. GOOLMAN.
